UNITED STATES PATENT OFFICE

HARRY D. KREMER, OF LEXINGTON, KENTUCKY

RAZOR-BLADE PROTECTOR

Application filed February 16, 1928. Serial No. 254,765.

This invention relates to razor blade protectors and has for an object to provide a device for the protection of a safety razor blade against damage from external causes 5 or from rust, erosion, corrosion or the like.

A further object of the invention is to provide a razor blade protector which comprises essentially a casing with pads impregnated with anhydrous rust preventing fluid 10 which close upon and embed a single razor blade therebetween with means for holding the casing in closed position, and other means for raising a part of one of the pads from closed position to lift the razor blade into position for access by the finger of the user.

A further object of the invention is to provide a razor blade protector having a body with a pad of impregnated material with an underlying spring or the like which tends to 20 lift the pad out of the body of the casing and to lift also the superimposed blade into position for convenient engagement by the finger of the user.

With these and other objects in view, the 25 invention comprises certain novel parts, elements, units, combinations, constructions, interactions and functions as disclosed in the drawings together with mechanical and functional equivalents thereof as will be herein- 30 after more fully described and claimed.

In the drawings:

Figure 1 is a view of the device in plan.

Figure 2 is a view of the device in edge elevation.

Figure 3 is a longitudinal sectional view 35 taken on line 3—3 of Figure 1 showing the device in closed and blade engaging position.

Figure 4 is a similar longitudinal section 40 showing the several parts in open position and the blade lifted.

Figure 5 is a plan view of the device open.

Figure 6 is a transverse sectional view taken 45 on line 6—6 of Figure 1.

Like characters of reference indicate 50 corresponding parts throughout the several views.

The improved razor blade protector which forms the subject matter of this application comprises a boxlike body 10 having hinged 55 thereto a lid 11 with the marginal flange 12

of the lid properly proportioned to enclose the body 10.

Within the body 10 a pad 13 is employed, which said pad is secured to the bottom of the body at one end, as indicated at 14, by any 55 cementitious material, the other end being free from attachment. The free end is provided with a cut-out part 15 properly proportioned to permit the insertion of a finger, as indicated at 16 in dotted lines at Figure 4, 60 to engage the razor blade 17 to remove such blade from the pad 13. To further assist in the convenience of removing the blade, a spring 18 is attached to the body at 19, and its free end is positioned to raise the free end of 65 the pad 13 to the position shown at Figure 4 whereby the finger 16 may be more conveniently inserted into the cut-out 15 for the removal of the said razor blade 17.

The lid 12 is also provided with a pad 20 70 which is preferably secured throughout the entire area of the lid, and the combined thickness of the pads 13 and 20 is such as to normally slightly more than fill the recess formed by the lid and body, requiring compression 75 of the materials of the pads which serves to clamp the razor blade 17 firmly between and to form a seal at the cutting edges of the razor blade.

The pads 13 and 20 are preferably composed 80 of animal fiber, which contains less moisture than vegetable fiber and is less liable to act corrosively upon the contained blade, and both the pads 13 and 20 will preferably be impregnated with an anhydrous oil which 85 will protect the blade from corrosion, assisting further in the formation of the seal about the cutting edges.

As shown in the drawings, the protector is 90 confined to a single type of razor blade but it is to be understood that the illustration of the particular blade is only a matter of convenience and that the protector will be made in any sizes or shapes and for the accommodation and protection of any and all types 95 of razor blades and that the showing of one particular type of razor blade is no limitation upon the invention.

The lid 12 and body 10 may be inter-associated in any approved manner. 100

As illustrated in the drawings, a hinge 21 connects the two units, and a latch or catch 22 retains the two parts in closed position when flanged together. It is to be understood, however, that the invention is in no way limited to the specific type of hinging or catch and that any means of inter-association of the two units is within the scope of the invention.

As hereinbefore pointed out, it is desirable that the pads 13 and 20 will be impregnated with an anhydrous oil, and the use of oils ordinarily available is, therefore, not considered wise. For this purpose, the device is provided with a can 23 having a screw cap 24 the can being reduced intermediate its ends to be inserted slidably into a pocket 25 formed upon one of the units. The reducing as mentioned provides a can having its enlarged end flush with the pocket 25 and for the purpose of removal and replacement, the edges of the can 23 are preferably knurled, as indicated at 26 which knurlings are formed along the wider part of the body of the can.

While the invention is in no way limited to the specific type of can or to any can in combination, it is desirable that such can shall accompany the protector for supplying as occasion may require the desired or requisite quality of oil for the proper protection of the blade.

From the foregoing description of the construction of the device, it is believed that its operation and utility will be fully understood and that further explanation will be superfluous.

What I claim to be new is:

1. A razor blade protector comprising a body unit and an overlapping lid unit, absorbent pads carried in proximate relation by the units, and means tending to flex one of the pads intermediate its ends to elevate one end out of its unit.

2. A razor blade protector comprising a body unit and a lid unit, absorbent pads carried upon proximate surfaces of the units, said pads being normally of greater thickness than the chamber formed by the co-acting units and adapted to embed a razor blade therebetween, and means to flex one of the pads intermediate its ends to raise one end of the pad for elevating the razor blade.

3. A razor blade protector comprising a body and lid, pads carried by proximate surfaces of the body and lid the combined thickness being normally greater than the capacity of the chamber formed by the inter-acting body and lid and adapted to clamp a razor blade therebetween, one of said pads being provided with a cut-out for convenience in manual engagement of the razor blade, and means to elevate said cut-out portion of the pad.

4. A razor blade protector comprising a body and lid, pads carried upon proximate

surfaces of the interacting body and lid, and a spring interposed beneath one end of one of the said pads, tending to flex said pad intermediate its ends to lift said end out of its unit.

5. A razor blade protector comprising body and lid units, absorbent pads carried by proximate surfaces of the units, one of said pads being secured adjacent one end of its unit and free adjacent its opposite end, and a spring interposed beneath the free end tending to flex said pad intermediate its ends to lift said free end out of said unit.

6. A razor blade protector comprising a body and a lid unit, absorbent pads carried by proximate surfaces of the units, one pad being secured at one end in its unit, the other end being free and provided with a cut-out, and a spring disposed beneath the free end tending to flex said pad intermediate its ends to lift said free end out of said unit.

In testimony whereof I affix my signature.
HARRY D. KREMER.
